Primary Examiner — Darcey E Gottschalk

(57) **CLAIM**

The ornamental design for an artificial lung ventilation apparatus, as shown and described.

DESCRIPTION

FIG. 1.1 is a front view of the artificial lung ventilation apparatus.

FIG. 1.2 is a back view of the artificial lung ventilation apparatus.

FIG. 1.3 is a left view of the artificial lung ventilation apparatus.

FIG. 1.4 is a right view of the artificial lung ventilation apparatus.

FIG. 1.5 is a top view of the artificial lung ventilation apparatus.

FIG. 1.6 is a bottom view of the artificial lung ventilation apparatus.

FIG. 1.7 is a front left perspective of the artificial lung ventilation apparatus.

FIG. 2.1 is a front view of an alternative embodiment of the artificial lung ventilation apparatus.

FIG. 2.2 is a back view of an alternative embodiment of the artificial lung ventilation apparatus.

FIG. 2.3 is a left view of an alternative embodiment of the artificial lung ventilation apparatus.

FIG. 2.4 is a right view of an alternative embodiment of the artificial lung ventilation apparatus.

FIG. 2.5 is a top view of an alternative embodiment of the artificial lung ventilation apparatus.

FIG. 2.6 is a bottom view of an alternative embodiment of the artificial lung ventilation apparatus.

FIG. 2.7 is a front left perspective view of an alternative embodiment of the artificial lung ventilation apparatus.

(Continued)

The broken lines depict portions of an artificial lung ventilation apparatus that form no part of the claim.
